In Germany May 28, 1930

4 Claims. (Cl. 250—27.5)

The invention relates to indirectly heated cathodes, the highly emissive surface of which consists of barium or a similar highly emissive metal.

Cathodes of this type should possess the following characteristics which, until now, could not all be secured in one device.

1. The emissive layer must adhere to the surface of the cathode in such a manner that it does not split away during the operation of the tube.

2. The cathode must possess a perfect equipotential area of good conductivity.

3. The equipotential area must be sufficiently insulated from the points of the filament which have different potentials.

4. The cathode must possess sufficient heat inertia so that the unavoidable small fluctuations in temperature of the filament will not cause audible fluctuations of the emission current.

5. The time required for heating the cathode should not be excessive.

6. No destructive stresses (mechanical pressure, tension) should result from the fluctuations in temperature of the cathode.

7. All electrical contacts must remain perfect at the temperatures concerned.

8. The construction of the cathode and its holders must be so strong that mechanical movements of the cathode with relation to the other parts of the system cannot occur, even when the entire valve is moved or shaken.

9. The remnant gases should be bound during the step of vaporizing the metallic barium on to the cathode surface.

35 The object of the invention is an indirectly heated cathode which is constructed in such a way as to fulfil simultaneously all of the stated conditions.

According to the invention, the insulating tube which may consist for example of porcelain, or fired mixtures of magnesia, silicates and the like is furnished, prior to the application of the barium, with a so tightly fitting metallic jacket that no portion of the barium, or at least 45 no essential proportion thereof, impinges the insulating material when the barium is vaporized on to the cathode. Said jacket may consist of a massive cylinder or a piece of sheet metal disposed round the tube, or also a closely wound wire spiral. In those cases in which the jackets possess small gaps through which parts of the insulator are exposed, these gaps, slits or the like are preferably so disposed that the main quantity of the barium vaporized on to the cathode is withheld therefrom. If a reaction mix-

ture is employed for producing the barium, and a slotted sheet metal jacket is employed, the side of the jacket remote from the slot is disposed opposite the reaction mixture.

The metal jacket is then coated with that particular metal on which the barium efficiently adheres and provides good emission for example tungsten. Said tungsten may be applied in the form of a tungsten wire wound upon the metal jacket. It may also be applied by means of spraying or by reduction of tungsten hexa-chloride.

According to the invention, the metallic base for the tungsten is made of a material which possesses a greater coefficient of expansion than tungsten or the particular metal which is applied to the metallic jacket. When employing tungsten wire as a carrier for the barium, there is preferably chosen a metallic cylinder composed of nickel. This, upon heating, expands to a greater extent than tungsten; the greater, therefore, the extent of heating, the more the tungsten wire presses against the nickel jacket. Thus shaky contacts or disturbing humming noises cannot occur. The tungsten wire may under certain circumstances fit so tightly against the nickel jacket that the same later, even after cooling, constitutes a unitary whole. In any case, however, the hitherto existing difficulty is overcome. Even should the insulating tube now possess a considerably smaller coefficient of expansion than the nickel jacket, the latter nevertheless forms such a solid unit that even with a certain looseness in the connection between porcelain tube and nickel jacket contact troubles or periodic contact or current fluctuations do not occur in the heated state.

According to a further object of the invention, insulating tubes are employed which, in proportion to their diameter, possess only a relatively small thickness (for example, .3 mm. thickness of wall with tubes .8 mm. thick). The use of insulating tubes of this kind having a comparatively great inner diameter allows of using a spiraled filament instead of the straight filament which otherwise must be employed. Since the emissive layer requires to be raised merely to a low temperature, the heating period, in accordance with requirement 5, is small, particularly as the heat capacity of the porcelain tube is considerably less owing to the reduced thickness. On the other hand, due to the low emission temperature, the cooling of the cathode is considerably less than in the case of higher temperatures. The loss of heat at those times when the filament is

traversed to a less extent, or not at all, by the current (i. e., in the case of A. C. heating at the times of the nodal points of the heating potential) is accordingly less than heretofore, and the 5 heat inertia of the cathode therefore greater.

Several embodiments of the invention are illustrated by the accompanying drawing in which Fig. 1 shows an electron discharge device containing the indirectly heated cathode according 10 to the invention, Fig. 2 shows a longitudinal section, Fig. 3 a cross-section of the cathode of the electron discharge device of Fig. 1 on a larger scale. Figs. 4 and 5 illustrate in equal manner another embodiment of the invention.

15 In Figs. 2 and 3 a tube 1 of insulating material, porcelain or zirconia or magnesia, the outer diameter of which may amount to between three and five times the thickness of the wall, is traversed by a single-thread spiral filament 2 of 20 tungsten wire which, must be raised to a temperature of more than 1000° (1100-1400°). The porcelain tube is surrounded by a nickel jacket 3 which, in the manner shown sectionally in Fig. 3, may be produced from a folded piece of sheet 25 metal. To this nickel jacket there is applied a layer of tungsten wire, for example wound in the form of a helix 4. The nickel base of this tungsten wire possesses at 5 the tapping contact which establishes an efficient conductive connection 30 with the single wire windings or other tungsten sections, and over the latter with the layer of barium 5 which is produced on the tungsten wire. If barium is vaporized on to the cathode in the manner illustrated diagrammatically by arrows 35 in Fig. 1, not only the tungsten wire is furnished with a thin coating of the metal, which later acts as emissive layer, but also the nickel is covered thereby. This barium deposited on the nickel serves as a gas binding agent during the 40 operation of the tube.

By the use of a slotted piece of sheet metal it is possible to secure the additional advantage 45 that the nickel jacket fits tightly against the porcelain tube in the warm state, as the slot in the nickel jacket contracts upon heating without limiting the degree of contact with the metal tube. This effect may be amplified by the counter-pressure exerted by a material having a smaller coefficient of expansion such as tungsten. Alternatively, a favourable distribution of pressure is 50 capable of being attained with the assistance of a nickel jacket, which is composed of windings of nickel wire (Fig. 4). Particularly desirable is an embodiment according to Fig. 5 (cross-section), in which the two edges of the sheet nickel overlap.

It has furthermore been found particularly suitable to apply a nickel base of this kind by means of the spray process. The nickel base may 55 also be produced electrolytically in the known

manner, after initially coating the surface of the tube with graphite or silver.

If there is first attached to the insulating tube the wire 5 by winding it thereon or by means of a sleeve, there is obtained, both when using the spraying method as well as galvanic separation of the nickel, the additional advantage that very good contact is produced between the equipotential cathode and the cathode tapping. Particular advantages are involved if the layer of nickel is 10 created by separation from a gaseous nickel compound, for example from a nickel-tetracarbonyl atmosphere. This is particularly suitable in systems with very weak heating power, which in consequence have only a very small thickness of porcelain tube and may therefore be very easily strained mechanically by the spraying process. 15

We claim:

1. An indirectly heated electron emitting cathode for an electron discharge device comprising 20 a heater filament, an insulating tube surrounding said heater filament, a metal layer surrounding said insulating tube, a further metal layer the coefficient of expansion of which is lower than that of the first metal layer surrounding 25 the first metal layer and consisting of a spiral wire, and a highly emissive layer surrounding the spiral wire.

2. An indirectly heated electron emitting cathode for an electron discharge device comprising 30 a heater filament, an insulating tube surrounding said heater filament, a metal layer surrounding said insulating tube, a further metal layer the coefficient of expansion of which is lower than that of the first metal layer surrounding the first 35 metal layer and consisting of a helix of tungsten wire, and a highly emissive layer surrounding said helix of tungsten wire.

3. An indirectly heated electron emitting cathode for an electron discharge device comprising 40 a heater filament, an insulating tube surrounding said heater filament, a metal layer surrounding said insulating tube, a further metal layer the coefficient of expansion of which is lower than that of the first metal layer surrounding the first 45 metal layer and consisting of a spiral wire, and a highly emissive layer of barium surrounding the spiral wire.

4. An indirectly heated electron emitting cathode for an electron discharge device comprising 50 a heater filament, an insulating tube surrounding said heater filament, a metal layer surrounding said insulating tube, a further metal layer the coefficient of expansion of which is lower than that of the first metal layer surrounding the first 55 metal layer and consisting of a helix of tungsten wire, and a highly emissive layer of barium surrounding said helix of tungsten wire.
